NEGATIVE RESISTANCE

Filed Jan. 24, 1922

Inventor.
M. M. Dolmage

UNITED STATES PATENT OFFICE.

MIHRAN M. DOLMAGE, OF WASHINGTON, DISTRICT OF COLUMBIA.

NEGATIVE RESISTANCE.

Application filed January 24, 1922. Serial No. 531,516.

This invention covers a new method for obtaining a negative resistance. It may be used in conjunction with high as well as low frequencies, including the range of frequencies of wireless telegraphy and telephony. It has the further advantage of being free from distortion and of being easily adjustable. The negative resistance described herein possesses the still further advantage in that it may be made to vary between very widely different limiting values.

The novel features of my invention I have pointed out in particularity in my claims. The invention itself will be best understood both as to its construction and method of operation, together with further objects and advantages, by reference to the following description taken in connection with the figure of the drawings which indicates the general arrangement of apparatus and wiring required to carry out my invention.

In the drawing, forming part of these specifications the combination of apparatus connected to terminals 1 and 2 to the right of the drawings represents a negative resistance. Connected to the last mentioned terminals, by dotted lines, are terminals 17 and 18 of an alternating source 1 in series with resistance 19. This resistance 19 includes the internal resistance of the generator and such additional resistance in series as the service requirements might demand. As an illustration, this alternating current source may be working over a given transmission line, in which case resistance 19 would represent the sum of the internal resistance of the alternating current source 1 and of the resistance of the line. Across terminals 1 and 2 is connected primary winding 3 of transformer A through two parallel paths—a path through primary winding 5 of shunt transformer B in series with resistance 7, and a second path through resistance 15 and secondary winding 14 of output transformer D of amplifier 16.

The secondary windings 4 and 6 of transformer A and B are connected in parallel to resistance 8 and primary winding 9 of input transformer of amplifier 16. The secondary winding of this same input transformer is connected to potentiometer 11. The potentiometer itself is connected to grid battery 12 and to the negative pole of filament battery 20. The plate circuit of

this same amplifier 16 is closed through a suitable plate battery and primary winding 13 of an output transformer. The secondary winding of this transformer is connected to resistance 15 and to the junction point of primary windings 3 and 5, as shown.

The system shown on the drawing, wired as just described, consists broadly of a network in which a given electromotive force (that of alternating current source 1) is amplified and reimpressed back upon this same network in such a direction as to overcome the electromotive force originally impressed. The arrangement will be made clearer by the following description of the method of operation of the system. Electromotive force E of alternator 1 forces a current through resistance 19 and winding 3 of transformer A. This current divides into two parts,—a part which flows through winding 5 of shunt transformer B, and a part which flows through resistance 15 and secondary winding 14 of output transformer of amplifier 16. The two secondary windings 4 and 6 are so connected as to force through resistance 8 and input transformer winding 9, currents in the same direction when alternator 1 is transmitting; and currents of opposite direction when amplifier 16 is transmitting through secondary winding 14 and resistance 15. This will be readily understood by reference to the drawing. When, therefore, the originally impressed electromotive force E is transmitting, the induced electromotive forces in the secondary parallel windings 4 and 6 are in the same direction with reference to the load,—viz, resistance 8 and primary winding 9 of input transformer C.

The electric current obtained in the manner just described, in the primary winding of input transformer C produces in the secondary winding 10 of this same transformer an induced electromotive force which is impressed, through potentiometer 11 and battery 12, upon the grid-filament circuit of amplifier 16. The corresponding amplified electromotive force is impressed upon the primary winding of output transformer D. The corresponding secondary electromotive force in winding 14 forces a current through resistance 15, which in turn divides itself into two parts—a part through transformer winding 3 and a part through transformer

winding 5. If amplifier 16 has been properly chosen as to its amplification constant and power capacity, and the connections properly made as to the relative phase of the 5 original electromotive force and of the electromotive force induced in the secondary winding 14, then the current due to this last mentioned electromotive force flowing through transformer winding 3 can be made 10 to far exceed in amplitude and to be in opposite phase to the current due to the original electromotive force E of alternating current source 1. The net result of the arrangement is that the resistance of the network, or system connected to terminals 1 15 and 2 to the right of the drawing, is negative since the current flowing through source 1, resistance 19 and transformer winding 3 is in actual phase opposition to the electromotive force of alternating current source 1. In order that the negative resistance thus obtained should be stable and free from reactive influences or "singing", it is sufficient that resistance 7 be so chosen in reference to resistance 19 as to secure a condition where the amplified electromotive force acting through transformer winding 14 can force no current through the input transformer winding 9 of the same amplifier. As an instance, if windings 3 and 5 are of equal number of turns and of equal 20 impedance and the corresponding secondary windings 4 and 6 bear the same equality relations to each other, then resistance 7 25 should be chosen equal to resistance 19. In such a case the currents, due to the amplified electromotive force acting through winding 14, flowing through windings 3 and 5 will be necessarily equal to each other and, 30 as the induced electromotive forces due to the two currents just mentioned are in phase opposition, no current will flow in input transformer winding 9. The system thus built is, therefore entirely free from "singing" tendencies and is otherwise absolutely 35 stable. The great ease with which the value of the negative resistance may be adjusted will be clear if it is realized that an adjustment of the potentiometer will result in a 40 change in the value of this negative resistance without it being necessary to make any other changes in the network. The wide 45 range of adjustment possible with the sys- 50 tem described in these specifications will also be clear if it is realized that, by a proper shifting of the potentiometer, the amplified electromotive force may be so reduced that there will be no current flow whatever through source 1 or winding 3. In such a case the negative resistance has obviously a value equal to infinity. A further increase in the value of the amplification, obtained through amplifier 16, will result in a reduction of the value of the negative resistance. 55 The choice of the various constants of the circuit may be derived by the following mathematical analysis: 60

Let us call

V =Electromotive force of an alternating current generator, having no internal impedance, connected directly to terminals 1 and 2 of the negative resistance as shown on Figure 1 of these specifications. 65

i_1 =Current through resistance 15 and secondary winding 14. 70

i_2 =Current through shunt transformer winding 5 and element 7. 75

A =Series resistance of grid circuit of amplifier 16 as measured through primary winding 9 and of resistance 8. 80

B =Series resistance of plate circuit, as measured through secondary winding 14, and of element 15. 85

Y =Resistance of element 7.

Y_1 =Resistance of element 19. 90

n_1 =Ratio of turns of winding 10 to winding 9.

n_2 =Ratio of turns of winding 13 to winding 14. 95

n =Ratio of turns of winding 5 to winding 6.

R_2 =Resistance of grid circuit as measured through winding 9. 100

R_3 =Resistance of element 15.

k =Coefficient of a value less than or equal to unity depending upon the position of the potentiometer. 105

$a = k \frac{n_1}{n_2}$

In order to simplify the analysis, we will assume that windings 3 and 4 have unity ratio of turns, and further that secondary windings 4 and 6 have the same impedance. Under these conditions the equations of the 110 electric circuit are as follows:—

$$(1) \quad V = A[i_1 + (n+1)i_2] + Bi_1 + V'$$

$$(2) \quad V = A[i_1 + (n+1)i_2] + nA[i_1 + (n+1)i_2] + Yi_2$$

$$(3) \quad V' = A[i_1 + (n+1)i_2] k \mu \frac{n_1}{n_2} \cdot \frac{R_2}{A}$$

It must be evident that the current flowing through secondary winding 4 is equal to $(i_1 + i_2)$ and the current flowing through winding 6 equal to (ni_2) . Therefore the current through elements 9 and 10 must equal the sum of the above two currents or 110 $i_1 + (n+1)i_2$. Hence the electromotive force impressed upon winding 10 is $R_2[i_1 + (n+1)i_2]$. 115

This electromotive force is multiplied by n_1 (ratio of turns of secondary winding 10 to

primary winding 9), again multiplied by k (a coefficient less than unity depending for its numerical value upon the position of the potentiometer), then again multiplied by μ (which is the amplification constant of the vacuum tube) and is divided by n_2 . The value thus finally obtained is that of V' of equation (3) above.

Introducing the value of V' , determined as explained, into equation (1) and, as a matter of convenience, rearranging equations (1) and (2) in function of i_1 and $i_1 + (n+1)i_2$

15

instead of i_1 and i_2 , we obtain—

$$(4) \quad V = A \left[1 + \frac{R_2 k \mu}{A} \cdot \frac{n_1}{n_2} \right] \left[i_1 + (n+1)i_2 \right] + Bi_1$$

$$(5) \quad V = \left[A(n+1) + \frac{Y}{n+1} \right] \left[i_1 + (n+1)i_2 \right] - \frac{Y}{n+1} i_1$$

In what follows we will represent

$$\left(\mu k \frac{n_1}{n_2} \right)$$

by (a). Solving equations (4) and (5), we obtain:—

$$(6) \quad i_1 = V \frac{A \left[n - \frac{R_2}{A} a \right] + \frac{Y}{n+1}}{B \left[A(n+1) + \frac{Y}{n+1} \right] + \frac{Y}{n+1} \left[A \left(1 + \frac{R_2}{A} a \right) \right]}$$

$$(7) \quad i_1 + (n+1)i_2 = V \frac{B + \frac{Y}{n+1}}{B \left[A(n+1) + \frac{Y}{n+1} \right] + \frac{Y}{n+1} \left[A \left(1 + \frac{R_2}{A} a \right) \right]}$$

Then, from the above two equations:—

$$(8) \quad i_2 = \frac{V}{n+1} \frac{B - A \left(n - \frac{R_2}{A} a \right)}{B \left[A(n+1) + \frac{Y}{n+1} \right] + \frac{Y}{n+1} \left[A \left(1 + \frac{R_2}{A} a \right) \right]}$$

What we particularly wish to obtain is the value of $(i_1 + i_2)$. It is given by:

$$(9) \quad (i_1 + i_2) = \frac{V}{n+1} \frac{nA \left[n - \frac{R_2}{A} a \right] + Y + B}{B \left[A(n+1) + \frac{Y}{n+1} \right] + \frac{Y}{n+1} \left[A \left(1 + \frac{R_2}{A} a \right) \right]}$$

We readily see from the above that the total equivalent resistance of the circuit, as given by

$$\frac{V}{i_1 + i_2}$$

is equal to

$$(10) \quad \text{Resistance} = \frac{BA(n+1)^2 + BY + Y \left[A \left(1 + \frac{R_2}{A} a \right) a \right]}{nA \left(n - \frac{R_2}{A} a \right) + Y + B}$$

To obtain further simplification we will show the following values for A and B in function of a single quantity Y_0 , as follows:—

$$(11) \quad A = \frac{Y_0}{n(n+1)}$$

$$(12) \quad B = \frac{Y_0}{n+1}$$

where Y_0 is a resistance.

Substituting the value of A and B given above into equation (10), we obtain:—

$$(13) \quad \text{Resistance} = \frac{Y_0}{n} \frac{\frac{R_2}{A} a Y + (n+1)(Y_0 + Y)}{\frac{R_2}{A} a Y_0 + (n+1)(Y_0 + Y)}$$

The resistance of the arrangement described in these specifications, as given by equation (13), depends therefore upon (Y), (Y_0), (n), (R_2) and (a). We can therefore vary or adjust this resistance by varying any one of the above mentioned quantities. The sign of the resistance, as given in formula (13), depends upon the sign of the denominator. If we so choose (a) that

$$\frac{R_2}{A}aY_0$$

is in excess of $(n+1)(Y+Y_0)$, then the denominator is negative and the resistance of our circuit, as measured between terminals 1 and 2, will also become negative.

The system described under these specifications is absolutely stable and free from "singing" tendencies if used in an electrical network of constant resistance or impedance. It is sufficient, in order to obtain this condition, that the resistance of the outside circuit connected to terminals 17 and 18, as measured from terminals 1 and 2, equal in value resistance 7 divided by (n). In such a case resistance 8 and input transformer winding 9 are connected to points of the same potential and therefore no alternating current flows through the grid-filament circuit of amplifier 16, and hence there can be no "singing" tendency established. This point is evident where (n) equals 1. Where (n) is different from 1, the "singing" equation 18 shows that if Y equals nY_1 , the amplification of bulb 16 may have a value equal to ∞ without producing any reactive tendencies in the network.

The negative resistance forming the object of the present disclosure is not, however, limited in its use to conditions of constant outside impedance. It may be used with varying outside impedance conditions provided such variation is kept within certain limits.

Referring again to the drawing and using

$$ni_2 - i_1 = E \left(\frac{n}{Y+Y_0} \right) - \frac{E}{Y_1 + \frac{Y_0}{n}} = \frac{En}{Y+Y_0} - \frac{En}{nY_1 + Y_0}$$

The potential (v') across winding 9, thus established, is equal to:—

$$v' = R_2(ni_2 - i_1) = R_2E \left[\frac{1}{Y+Y_0} - \frac{1}{nY_1 + Y_0} \right]$$

If $R_2 = A$, then

$$v' = E \times \frac{Y_0}{n+1} \times \frac{(nY_1 - Y)}{(Y+Y_0)(nY_1 + Y_0)}$$

Since $E = v$ (a), we write

$$v' = v(a) \frac{Y_0}{n+1} \frac{nY_1 - Y}{(Y+Y_0)(nY_1 + Y_0)}$$

the notation already established, assume that a potential (v) is established across transformer winding 9 for a short period of time. This potential is increased (n_1) times, multiplied μk times and divided by (n_2), as already explained in detail. The plate potential of amplifier 16 is therefore equal to

$$E = v \left(\mu k \frac{n_1}{n_2} \right) = v(a) \quad 55$$

To determine the resulting electromotive force (v') across transformer winding 9, we will write the controlling equations, which are:—

$$\begin{aligned} E &= B(i_1 + i_2) + Y_1 i_2 + nA(ni_2 - i_1) \\ E &= B(i_1 + i_2) + Y_1 i_1 + A(i_1 - ni_2) \end{aligned}$$

where

i_1 = Current through transformer winding 3 and outside circuit having a resistance equal to Y_1 .

i_2 = Current through transformer winding 5 and resistance Y .

$$\begin{aligned} E &= i_1(B - nA) + i_2(B + Y + n^2A) \\ E &= i_1(B + Y_1 + A) + i_2(B - nA) \end{aligned} \quad 70$$

If we make, as before—

$$A = \frac{Y_0}{n(n+1)} \quad B = \frac{Y_0}{n+1} \quad 75$$

Then

$$B - nA = 0$$

Referring to the above equations relating to i_1 and i_2 , we see that with the relation $B = nA$, the value of i_1 and i_2 may be immediately deduced as follows:—

$$\begin{aligned} i_1 &= \frac{E}{B + Y_1 + A} \quad i_2 = \frac{E}{B + Y + n^2A} \quad 85 \\ i_1 &= \frac{E}{Y_1 + \frac{Y_0}{n}} \quad i_2 = \frac{E}{Y + Y_0} \end{aligned}$$

The current through transformer winding 9 is equal to $(ni_2 - i_1)$, hence it is equal to

If (v') is smaller than (v), then the system cannot "sing", hence the necessary condition to obtain stability is given by

$$v(a) \times \frac{Y_0}{n+1} \times \frac{nY_1 - Y}{(Y+Y_0)(nY_1 + Y_0)} < v \quad 105$$

which means that the constant (a) must not exceed—

$$\frac{(Y+Y_0)(nY_1 + Y_0)}{(nY_1 - Y)} \times \frac{(n+1)}{Y_0} \quad 110$$

If the resistance Y_1 of the outside circuit, instead of being constant and equal to $\frac{Y}{n}$, is variable, we may assume $nY_1 = pY$ where ⁵ (p) is some numeric in excess of unity. Then

$$a < \frac{(Y + Y_0)(pY + Y_0)(n+1)}{(p-1)YY_0}$$

¹⁰ or

$$(14) \quad \frac{a \cdot YY_0}{(n+1)(Y + Y_0)} < \frac{pY + Y_0}{p-1}$$

¹⁵ If we establish a relation between (a_0) , the maximum amplification possible with the amplifier installation available, and (Y_1Y_0) and $(n+1)$ as follows:—

$$(15) \quad a_0Y_0 = 2(n+1)(Y + Y_0)$$

Then the above inequality may be written as follows:—

$$2Y < \frac{pY + Y_0}{p-1}$$

which leads to the simple relation

$$(16) \quad \frac{Y_0}{Y} > p - 2$$

It is therefore clear that within extremely wide limits we may choose $\frac{Y_0}{Y}$ so that it will exceed $(p-2)$ and obtain a stable electrical network. If (p) is less than 2, we can assume any positive value we wish for (Y_0) . If (p) is in excess of 2, we can assume a value just less than that given by the relation $Y_0 = Y(p-2)$

The minimum value of the negative resistance of our special network is given by—(see formula 13)

$$\text{Negative resistance} = -\frac{Y_0}{n} \frac{a_0Y + (n+1)(Y + Y_0)}{a_0Y_0 - (n+1)(Y + Y_0)}$$

$$\text{Negative resistance} = -\frac{Y_0}{n} \frac{a_0Y_0 \left(\frac{Y}{Y_0} \right) + (n+1)(Y + Y_0)}{a_0Y_0 - (n+1)(Y + Y_0)}$$

$$\text{Negative resistance} = -\frac{Y_0}{n} 2 \left(\frac{Y}{Y_0} \right) + 1$$

$$(17) \quad \text{Negative resistance} = -\frac{2Y + Y_0}{n}$$

in view of formula (15).

The minimum value of the negative resistance may also be expressed, provided (p) is in excess of 2, by the formula

$$45 \quad \text{Negative resistance} = -p \frac{Y}{n}$$

in view of formula (16).

It will be noted that the value of the negative resistance network, as given by formula (13), is independent of the degree of balance or lack of balance between element 19 and element 7 of the drawing. In the derivation of the fundamental equations no definite numerical relationship was assumed between these two elements and these equations hold regardless of the relation between these elements, provided the unbalance is not such as to cause "singing."

60 The special network described under these specifications is a negative resistance independent of frequency, since its value is given by formula (15) in which both Y and Y_0 are pure resistances. It may therefore be used for high as well as low frequencies. It may be adjusted within extremely wide limits—

65 between infinity and $-p \frac{Y}{n}$. Another very important characteristic of the combination described hereinabove is that it provides a

stable, non-oscillating negative resistance. It is possible for instance, to calibrate the potentiometer 11, so that it will read directly in ohms of negative resistance produced by the apparatus. This negative resistance ⁷⁵ will stay fixed in value so long as the amplifying power of the amplifying bulb (13) is maintained constant.

The uses to which a negative resistance, as hereinbefore specified, may be put are so many that no attempt will be made to give a complete list of such uses. A most important application consists in its use in the main antenna circuit of a radio receiving system, greatly increasing thereby the total amplification without bringing in any additional tendency to "sing". Essentially the arrangement described is a "bridge" and therefore complete freedom from "singing" may be obtained provided element 7 matches element 19. It is also possible to reverse the wiring between elements 5 and 7 on one hand and elements 15 and 14 on the other hand and secure a new range of negative resistances.

⁹⁰ ⁸⁵ ⁹⁵
Claims:—

1. An electrical network, means to connect said network to an outside circuit, an amplifier in said network, means to impress the output electromotive force of said am-

- plifier upon the outside circuit in opposition of phase to the initial flow of current from said outside circuit to said network.
2. An electrical network, means to connect said network to an outside circuit, an amplifier in said network, means to prevent the "singing" of said amplifier, means to impress the output electromotive force of said amplifier upon the outside circuit in opposition of phase to the initial flow of current from said outside circuit to said network.
3. An electrical network, means to connect said network to an outside circuit, an amplifier in said network, means to vary the output electromotive force of said amplifier and to impress said electromotive force upon the outside circuit in opposition of phase to the initial flow of current from said outside circuit to said network.
4. An electrical network, means to connect said network to an outside circuit, an amplifier in said network, means to prevent the "singing" of said amplifier, means to vary the output electromotive force of said amplifier and to impress said electromotive force upon the outside circuit in opposition of phase to the initial flow of current from said outside circuit to said network.
5. An electrical network having a negative resistance independent of frequency, means to connect said network to an outside circuit, an amplifier in said network, means to impress the output electromotive force of said amplifier upon the outside circuit in opposition of phase to the initial flow of current from said outside circuit to said network.
6. An electrical network having a negative resistance independent of frequency, means to connect said network to an outside circuit, an amplifier in said network, means to prevent the "singing" of said amplifier, means to impress the output electromotive force of said amplifier upon the outside circuit in opposition of phase to the initial flow of current from said outside circuit to said network.
- cuit, an amplifier in said network, means to prevent the "singing" of said amplifier, means to impress the output electromotive force of said amplifier upon the outside circuit in opposition of phase to the initial flow of current from said outside circuit to said network.
7. An electrical network having a negative resistance independent of frequency, means to connect said network to an outside circuit, an amplifier in said network, means to vary the output electromotive force of said amplifier and to impress said electromotive force upon the outside circuit in opposition of phase to the initial flow of current from said outside circuit to said network.
8. An electrical network having a negative resistance independent of frequency, means to connect said network to an outside circuit, an amplifier in said network, means to prevent the "singing" of said amplifier, means to vary the output electromotive force of said amplifier and to impress said electromotive force upon the outside circuit in opposition of phase to the initial flow of current from said outside circuit to said network.
9. In combination, a bridge circuit containing an amplifying system with its initial input and final output circuits occupying opposite arms, an outside circuit and a balancing network also occupying opposite arms in said bridge, an electromotive force in said outside circuit and means to superimpose upon said outside circuit the electromotive force of the final output circuit of said amplifying system.

In testimony whereof I affix my signature.

MIHRAN M. DOLMAGE.
